CLAIM

The ornamental design for an oilfield hydration unit, as shown and described.

DESCRIPTION

FIG. 1 is a top left perspective view of an oilfield hydration unit that embodies the ornamental design;

FIG. 2 is a front elevation view of the oilfield hydration unit;

FIG. 3 is a rear elevation view of the oilfield hydration unit;

FIG. 4 is a left side elevation view of the oilfield hydration unit;

FIG. 5 is a right side elevation view of the oilfield hydration unit;

FIG. 6 is a top plan view of the oilfield hydration unit; and,

FIG. 7 is a bottom plan view of the oilfield hydration unit. Dashed lines shown in the drawings illustrate unclaimed features of the ornamental design.
